Patented May 16, 1933

1,909,645

UNITED STATES PATENT OFFICE

LOUIS WIESNER, OF BROOKLYN, NEW YORK

SLIPPER

Application filed December 29, 1931. Serial No. 583,664.

This invention relates to new and useful improvements in a slipper.

The invention has for an object the construction of a slipper which is characterized by the provision of a bulldog's or similar face formed upon the vamp portion thereof with the nose bulged from the vamp portion to simulate the true nose of a dog.

The invention has for a still further object the arrangement of a tongue insert secured upon the vamp portion to simulate the dog having its tongue extended.

As another object of this invention it is proposed to provide means for adjustably holding the tongue at various extended positions.

Furthermore, the invention also proposes the construction of a last with a bulged portion adapted to readily manufacture the slipper above mentioned.

Another one of the objects of this invention is the construction of an article of the class described which is of simple durable construction, dependable in use and efficient in action and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a slipper constructed according to this invention.

Fig. 2 is a side elevational view of Fig. 1.

Fig. 3 is a fragmentary sectional view taken on the line 3—3 of Fig. 1.

Fig. 4 is a fragmentary inside elevational view of the vamp of the slipper seen as though looking in the direction of the line 4—4 of Fig. 3.

Fig. 5 is a view similar to Fig. 3 but illustrating a modification of the invention.

Fig. 6 is an elevational view as though taken on the line 6—6 of Fig. 5.

Fig. 7 is a perspective view of the last used in the manufacture of the slipper.

The slipper, according to this invention, is composed of a slipper upper 10 attached between an outer sole 11 and an inner sole 12. The outer sole 11 preferably should be made of soft leather and the inner sole 12 of flannel or the like pad material. The shoe upper 10 preferably should be made of felt or other material from which slippers are generally made. The vamp portion 13 of the slipper upper is formed with a bulged portion 14 adapted to simulate the nose of a bulldog. This bulged portion is formed in the manufacture of the slipper by reason of having a similar bulge 15 upon a last 16 used in the manufacture of the same. The front portion 17 of the last is rounded as indicated by numeral 18, so as to accentuate the proper shape of the bulldog head.

Trimming material is arranged upon the vamp portion to form the features of the bulldog. More particularly, there is a piece of material 19 shaped so as to form the ears 19 and the jaw portion 20 of the dog. Eyes 21 are secured upon the material 18 at the correct portion thereof. Embroidery 22 or the like is arranged on the bulged portion 14 to conclude the representations of the dog's nose and also the mouth 23.

A small strip of material 24 is extended at the mouth and arranged so as to simulate the dog's tongue. This strip of material extends through a slit 25 in the vamp portion of the slipper to the rear side. A reinforcement sheet 26 is secured upon the rear side upon the vamp portion of the slipper over the inner end of the tongue 24 and serves to firmly hold the tongue in place.

The modified form of the device illustrated in Figs. 5 and 6 shows a means for holding the tongue of the dog in various extended positions. More particularly, the tongue is indicated by reference numeral 27 and is shown attached upon an elastic strip 28 which is secured at its free end 29 within the vamp of the shoe. The tongue 27 and strip 28 engage in between a pair of jaws 30. One of the jaws is attached by stitches 31 to the inside of the vamp portion of the shoe. Screws 32 engage through the vamp portion and through this jaw and threadedly extend 100

into bosses 33 formed in the other jaw. The screws 32 straddle the tongue 27 and strip 28 as clearly shown in Fig. 6. When the screws 32 are slightly loosened the jaws release the tongue of the elastic strip 28 returns it into substantially its fully retracted position. Then it may be drawn out any distance and the screws 32 tightened so that the jaws hold the tongue in the new position. A reinforcement patch 34 is extended within the vamp across the bulged portion thereof so as to cover the jaw construction. If the screws 32 are left loose, the tongue 27 may be pulled by the child as an entertainment.

15 It is to be understood that not only bulldog face but any other animal or human face may be used in accordance with my invention in which the bulging of face is accentuated.

20 While I have shown and described the preferred embodiment of my invention, it is to be understood that I do not limit myself to the precise construction herein disclosed and the right is reserved to all changes and modifications coming within the scope of the invention as defined in the appended claims.

25 Having thus described my invention, what I claim is new, and desire to secure by United States Letters Patent is:

30 1. A slipper, comprising an upper section with a vamp portion bulged to simulate the nose of a bulldog or the like, trimming on the vamp portion to conclude the face of the bulldog or the like, a tongue extended through the bulged vamp portion, an elastic strip attached to the inner end of the tongue forming a means for making said tongue extendable, a pair of jaws straddling said tongue and elastic strip, and means for clamping the jaws together to hold the tongue in various 35 extended positions comprising screws engaging through one of the jaws and threaded 40ly engaging into bosses formed upon the other jaw.

45 2. A slipper, comprising an upper portion bulged at the vamp section to simulate the nose of a bulldog, trimming on the outside of the vamp section to conclude the formation of the face, and a tongue strip being engaged through the vamp portion and secured upon 50 the inside thereof.

55 3. A slipper, comprising an upper portion bulged at the vamp section to simulate the nose of a bulldog, trimming on the outside of the vamp section to conclude the formation 60 of the face, and a tongue strip being engaged through the vamp portion and secured upon the inside thereof, the securing being accomplished by a patch secured on the inside of the vamp portion of the tongue.

65 4. A slipper, comprising an upper section with a vamp portion bulged to simulate the nose of a bulldog or the like, trimming on the vamp portion to conclude the face of the bulldog or the like, a tongue extended 70 through the vamp portion, an elastic strip

attached to the inner end of the tongue forming a means for making said tongue extendable, a pair of jaws straddling said tongue and elastic strip, and means for clamping the jaws together to hold the tongue in various extended positions comprising studs engaging through one of the jaws and detachably secured to the other jaw.

75 5. A slipper, comprising an upper section with a vamp portion bulged to simulate the nose of a bulldog, trimming on the vamp portion to conclude the face of the bulldog, a tongue extended through the vamp portion, an elastic strip attached to the inner end of the tongue, a pair of jaws straddling said tongue and elastic strip, and means for clamping the jaws together to hold the tongue in various extended positions.

80 6. A slipper, comprising an upper portion bulged at the vamp section to simulate the nose of a bulldog, trimming on the outside of the vamp section to conclude the formation of the face, a tongue included in said face and comprising a strip of material engaged through the vamp portion of the slipper, and means for holding the tongue in various extended positions.

85 7. A slipper, comprising an upper portion bulged at the vamp section to simulate the nose of a bulldog, trimming on the outside of the vamp section to conclude the formation of the face, a tongue included in said face and comprising a strip of material engaged through the vamp portion of the slipper, and means for holding the tongue in various extended positions, said tongue being attached upon an elastic element tending to normally draw it completely inwards.

90 8. A slipper, comprising an upper section with a vamp portion bulged to simulate the nose of a bulldog or the like, trimming on the vamp portion to conclude the face of the bulldog or the like, a tongue extended through the vamp portion, an elastic strip attached to the inner end of the tongue forming a means for making said tongue extendable, a pair of jaws straddling said tongue and elastic strip, and means for clamping the jaws together to hold the tongue in various 95 extended positions.

100 In testimony whereof I have affixed my signature.

LOUIS WIESNER.
